CHAIR ATTACHMENT

Jodie A. Nobbe, St. Paul, Minn.

Application March 2, 1954, Serial No. 413,631

4 Claims. (Cl. 155—127)

This invention relates to an attachment whereby an armless side chair may be adapted to accommodate an infant or youth. It provides a combination comprising an arm rests, a food tray, and a footrest, which may quickly and easily be attached, as a unit, to a chair, to render that chair safe and suitable for an infant or young person. Although the attachment is particularly adapted for use on a chair, the legs and back of which are formed from tubular cylinders, it nevertheless can feasibly be used upon other types of chairs, as well.

It is, of course, well known that infants and small children, when being fed, must be placed in a chair which holds them safely against falling. For this purpose, so-called "high chairs" are customarily used. However, chairs of that kind are not suitable for any use other than their specific intended use; i. e., the feeding of an infant. They are not convertible for use by adults.

It is an object of the present invention to provide an attachment which will permit use of the same chair by both an adult, and an infant. By reason of this invention, the necessity of keeping a special high chair is eliminated. My attachment, when not in use, can be stored without occupying much room, and the chair upon which it was affixed can be used for other purposes. The expense of two chairs is thereby done away with, and there is no longer the need for finding space (in small apartments, etc.) to store two separate items of furniture.

It is a further objective of this invention to provide a chair attachment which may very easily be attached to any standard type of chair made from tubular material. It is also an object of the invention to provide an attachment which is adjustable for use with children of various sizes, which is durable, and which may be satisfactorily produced at reasonable cost.

Other objects and advantages of the invention will appear as this description proceeds.

Referring now to the drawings, Figure 1 is a side elevational view of a chair, with my attachment mounted upon it.

Figure 2 is a front elevational view of the chair, also having the attachment upon it.

Figure 3 is a cross-sectional view along the lines 3—3 of Figure 1.

Figure 4 is a cross-sectional view of a "cuff" arrangement, whereby the attachment is secured onto the chair leg member.

Figure 5 is an inside elevational view of the front portion of one of the arms in my attachment.

Figure 6 is an inside elevational view of the horizontal portion of one of the arms in my attachment.

Referring now to the drawings in more detail, reference character 1 indicates generally a chair having bent tubular leg members 2 and 3 and tubular back support member 4. The lower ends of each of the legs are furnished with rubber cups 5. Seat cushion 6 lies over said leg members, and back cushion 7 is affixed to tubular back support member 4. The chair illustrated is one standard form of chair (made from tubular material) now sold in large volume. Other standard chairs made from such material differ in specific points of construction, but my attachment is suitable for use on any of such standard types, to the best of my knowledge.

My attachment comprises, first, two lengths of tubular material 8 and 9 which function as side arms for the chair when my attachment is mounted on said chair. The end portions 10, 10a and 11 of each of said arms are bent

acutely to the mid-portion thereof, so that each said mid-portion will be spaced upwardly from the seat of the chair a distance sufficiently great to prevent an infant from falling sidewise out of the chair. I prefer that 5 each of tips 10—11 be turned inwardly toward each other, as shown, so that the attachment of said tips to the chair leg members (in the manner hereinafter described) will not be interfered with by seat cushion 6.

Each of the end portions 10—11 of said arms is provided with cylindrical cuff-like arrangements 12, 12a, and 13, by means of which said arms may each be attached to said chair leg members. The inner periphery of each of said cuffs is provided with a lining of resilient material 14, such as rubber, to avoid said cuffs' scratching the surface of the chair legs, and to provide better gripping action of said cuffs upon the legs. The end of each of said cuffs is turned backwardly as at 15 and 15a, and is forked as at 16. End portion 15a of said cuffs is provided with bolt 17. Said bolt is pivotal in relation to 15 each cuff and may be drawn up and inserted in fork 16. Wing nut 18 may then be tightened down on bolt 17 to hold said cuff tightly in position about the leg.

The inwardly facing surface of the horizontal portion of each of said arms 8 and 9 is provided with a series of aligned apertures 19. The underside of tray 20 is provided, at opposed edge portions, with two spring operated catch elements 21 and 22. These elements have tongues 23 and 23a which are of a size to be receivable within an opposed pair of apertures 19. These tongues 30 are horizontally movable by operation of knobs 24 and 25. The edge portions of tray 20 are formed with hooks 26 and 27 which overlie arms 8 and 9 and serve to keep those arms from being spread apart from each other, when the attachment is in use. Said arms are prevented from converging toward each other when the attachment is in use by the presence of tray 20 between them. It will be apparent that tray 20 can be moved forwardly or backwardly to accommodate children of various sizes by disengaging tongues 23 and 23a from apertures 19 and moving said tongues either forwardly or backwardly to another pair of opposed apertures.

The inner surface of the forward, upstanding portion of each side arm is provided with a series of angled slots 28. The slots on each of said side arms are opposed. 45 Footrest 29 comprises a planar foot supporting member 30 slung in a rigid strap member 31. The end portions 32 and 33 of said strap member are bent outwardly, and each end is adapted for placement in one of slots 28. Said planar footrest may be secured to said strap member by any suitable means, such as rivets. By reason of the angle of slots 28, and the rigidity of strap 31, footrest 29 projects forwardly, at an angle, from the attachment so that it will be in position most suitable to receive the infant's feet. As again will be apparent, the height of said footrest can be adjusted by raising or lowering the ends of strap 31 into another pair of opposed slots. Said footrest, in a lower position, is shown by dotted lines in Figure 1.

It will be apparent that the specific construction shown and described herein could be modified in detail, or arrangement of parts, without departing from the spirit of my invention. The particular elements above described are exemplary, and I do not intend to limit myself to those specific elements, other than as such are set forth in the claims annexed hereto.

What I claim is:

1. An attachment for an adult's armless chair having tubular leg members whereby said chair may be adapted to accommodate an infant or youth, said attachment comprising a pair of arms, a tray, and a footrest, each of said arms having upstanding end portions, and a horizontal mid-portion, the end portions of each of said arms being provided with means whereby said arms may be removably affixed to said tubular leg members in parallel position along the sides of said chair, the mid-portions of each of said arms being provided with a series of aligned apertures, opposed edge portions of said tray being provided with slideable catch elements adapted to engage said apertures, opposed front end portions of said arms being provided with a series of aligned slots, said footrest comprising a planar foot supporting member

slung in a rigid strap member, the ends of said strap member being adapted for placement in a pair of opposed slots, said tray being adjustable forwardly and backwardly, said footrest being adjustable upwardly and downwardly.

2. An attachment for an adult's armless chair having tubular leg members whereby said chair may be adapted to accommodate an infant or youth, said attachment comprising a pair of arms, a tray, and a footrest, each of said arms comprising a length of rigid tubular material, the end portions of each of said arms being bent in the same direction acutely to the mid-portions thereof, the tips of said arms being provided with means for affixing said arms to the tubular leg members of said chair in parallel relationship along the sides of said chair with the end portions of said arms upstanding, the mid-portions of said arms each being provided with a series of aligned apertures, opposed edge portions of said tray being provided with slideable catch elements adapted to engage said apertures to maintain said tray on said arms and to maintain said arms in spaced apart parallel position, the front end portions of said arms being provided with a series of aligned slots, said footrest comprising a planar foot supporting member slung in a rigid strap member, the ends of said strap member being adapted for placement in a pair of opposed slots, said tray being adjustable forwardly and backwardly, said footrest being adjustable upwardly and downwardly.

3. An attachment for an adult's armless chair having tubular leg members whereby said chair may be adapted to accommodate an infant or youth, said attachment comprising a pair of arms, a tray, and a footrest, said arms being congruent and each comprising a length of rigid tubular material, the end portions of each arm being bent in the same direction acutely to the mid-portion thereof, the tips of said arms being provided with cuffs adapted for placement about said tubular leg members, said cuffs including means whereby said cuffs may be tightened upon said tubular leg members to maintain said arms in position along the sides of said chair, the inwardly facing mid-portions of said arms each being provided with a series of aligned apertures, opposed edge portions of said tray being provided with slideable catch elements adapted to engage said apertures, the same opposed edge portions of said tray being formed with hooks adapted to overlie the outwardly facing mid-portions of said arms, said catch elements and said hooks cooperating to maintain said arms in parallel, spaced apart position, the

front end portions of said arms being provided with a series of aligned slots, said footrest comprising a planar foot supporting member slung in a rigid strap member, the ends of said strap member being adapted for placement in a pair of opposed slots, said tray being adjustable forwardly and backwardly said footrest being adjustable upwardly and downwardly.

4. An attachment for an adult's armless chair having tubular leg members whereby said chair may be adapted to accommodate an infant or youth, said attachment comprising a pair of arms, a tray, and a footrest, said arms being congruent, each arm having upstanding end portions, and a horizontal mid-portion, the end portions of each of said arms converging toward each other as they extend away from said mid-portion, the tips of each of said end portions being provided with a cuff adapted for placement about a tubular leg member, said cuffs including means whereby said cuffs may be tightened about said tubular leg members to maintain said arms in position along the sides of said chair, the inwardly facing mid-portions of each of said arms each being provided with a series of aligned apertures, opposed edge portions of said tray being provided with slideable catch elements adapted to engage said apertures, the same opposed edge portions of said tray being formed with hooks adapted to overlie the outwardly facing mid-portions of said arms, said catch elements and said hooks cooperating to maintain said arms in parallel, spaced apart position, the front end portions of said arms being provided with a series of aligned slots, said footrest comprising a planar foot supporting member slung in a rigid strap member, the ends of said strap member being adapted for placement in a pair of opposed slots, said tray being adjustable forwardly and backwardly, said footrest being adjustable upwardly and downwardly.
